CLOSURE

William Baker, Toledo, Ohio

Application September 29, 1933, Serial No. 691,429

8 Claims. (Cl. 215—8)

This invention relates to closures for containers and particularly to closures for bottles provided with means for indicating whether or not such closures have been opened for the removal of the 5 contents.

The principal object of the invention is the provision of a fitting having an inaccessible lock to prevent the removal of the fitting from a bottle neck.

Another object is the provision of a fitting and bottle neck with a ratchet and pawl lock to prevent removal of the fitting from the bottle neck.

Another object is the provision of a fitting adapted to be screwed onto a bottle neck, the 15 bottle neck and fitting being provided with a ratchet and pawl device to prevent the fitting from being unscrewed from the bottle neck.

And still another object is the provision of a fitting having a nonreplaceable diaphragm which 20 may be broken, in combination with a bottle neck upon which the fitting is adapted to be screwed, and a ratchet and pawl lock to prevent the fitting from being unscrewed from the bottle neck.

Other objects and advantages will be apparent 25 from the following description, in which reference is had to the accompanying drawing illustrating a preferred embodiment of my invention and wherein similar reference numerals designate similar parts throughout the several views.

30 In the drawing:—

Figure I is a front elevational view, with parts broken away and parts in section, of a bottle equipped with a preferred form of the closure of my invention.

35 Figure II is a sectional plan view of the fitting and neck of the bottle taken substantially on the line II—II of Figure I.

Figure III is a vertical sectional view taken substantially on the line III—III of Figure II.

40 Referring to the drawing in detail, I have shown my closure applied to a bottle or flask 1, which may be of any desired shape and material. The neck 2 of the bottle is provided with a collar 3 having a shoulder on its upper side and 45 with a spiral series of protuberances 4 shaped as indicated in Figures I and II to constitute a combined thread and ratchet. The collar 3 and protuberances 4 are preferably formed integral with and of the same material as the bottle neck.

50 Fitted over the mouth of the bottle is an annular member 5, the interior face of which is provided with a helical groove 6, which, when the fitting is screwed upon the bottle neck, receives the helical series of protuberances 4. The direction 55 of the helixes formed by the series of protuber-

ances 4 and the groove 6 may be such as to form either a left-hand or a right-hand thread. A right-hand thread is shown in the drawing.

The fitting 5 may be made of metal, porcelain or glass, but it is preferably made of urea-formaldehyde resin or other plastic molding material. It is provided with a vertical socket 7, opening from its lower end, and lying within the socket 7 is a cylindrical portion 8 of a resilient pawl 9; the size of the cylindrical portion being such that it fits 10 tightly within the socket and engages the interior socket with expansive force, thus being reliably retained in place after assembly. I prefer to assemble the pawl 9 with the member 5 by pushing it into the socket after the member 5 has been 15 made, but if desired, the pawl 9 may be molded into the member 5 when the member 5 is made. When the fitting is screwed upon the bottle neck the resilient pawl 9 slides over the helical series 20 of ratchet-like protuberances 4, but if an attempt be made to unscrew the fitting, the tip of the pawl 9 catches on one of the protuberances and prevents the fitting from being unscrewed. The relative strengths of the fitting and pawl are such that if force be applied to the fitting in an 25 attempt to unscrew it the fitting will be destroyed before the pawl can be forced over the ratchet teeth. Access to the pawl is prevented by the shouldered collar 3. A gasket or liner 10 is 30 interposed between the top of the bottle neck and an internal shoulder on the annular member 5 to prevent leakage between the bottle neck and the annular member, the thickness and resilience of the liner 10 being such that leakage is prevented while the fitting 5 is more or less tightly 35 screwed into place; hence, the fitting, after being tightly screwed down, may be turned back until the pawl 9 engages the approximate protuberance 4, without loosening the gasket 10 sufficiently to prevent leakage around it.

Molded across the opening in the annular member 5 and lying somewhat below its upper end is an integral diaphragm or seal 11. A circular groove is molded into the seal or diaphragm adjacent its edge to provide an easily breakable 45 juncture, so that the diaphragm may be punched out with the finger or any elongated instrument, such as a pencil or key, which is small enough to be pushed into the opening. The upper portion of the member 5 is threaded as at 12 and screwed 50 upon the threaded upper portion is an internally threaded cap 13 provided with a liner or gasket 14 to prevent leakage between the member 5 and the cap 13.

Preferably, the cap 13 is assembled on the 55.

member 5 before the fitting is screwed upon the filled container. When it is desired to open the closure the cap 13 is unscrewed and the diaphragm 11 punched out. After opening, the cap 13 may be replaced to retain and preserve the contents of the bottle, but the broken diaphragm will remain evidence that the closure has been opened.

The embodiment of my invention herein shown 10 and described is to be regarded as illustrative only, and it is to be understood that the invention is susceptible to variation, modification and change within the spirit and scope of the subjoined claims.

15 Having described my invention, I claim:

1. In a device of the class described, in combination, a container element, a fitting element, an inaccessible lock to prevent removal of said fitting element from said container element, an 20 easily broken nonreplaceable diaphragm extending across an opening in said fitting element to prevent passage of the contents of said container element, and a removable and replaceable closure adapted for leak-proof application to said fitting 25 element.

2. In a device of the class described, in combination, a container element, a fitting element, an inaccessible lock to prevent removal of said fitting element from said container element, said 30 lock including a pawl on one of said elements engageable with a protuberance on the other of said elements, an easily broken nonreplaceable diaphragm extending across an opening in said fitting element to prevent passage of the contents 35 of said container element, and a removable and replaceable closure adapted for leak-proof application to said fitting element.

3. In a device of the class described, in combination, a container element, a fitting element, 40 one of said elements having a series of ratchet-like protuberances, the other element having a pawl engageable with said protuberances to prevent removal of said fitting element from said container element, an easily broken nonreplaceable diaphragm extending across an opening in 45 said fitting element to prevent passage of the contents of said container element, and a removable and replaceable closure adapted for leak-proof application to said fitting element.

50 4. In a device of the class described, in combination, a container having a neck provided with a helical series of ratchet-like protuberances, a fitting for said neck having a helical groove adapted to receive said protuberances and permit 55 said fitting to be screwed on said neck, a pawl carried by said fitting and adapted to engage one of said protuberances to prevent said fitting from being unscrewed from said neck, a frangible nonreplaceable diaphragm extending across an 60 opening in said fitting to prevent passage of the contents of said container, and a removable closure adapted for leak-proof application to said fitting.

5. In a device of the class described, in combination, a container having a neck provided with a helical series of ratchet-like protuberances, a fitting for said neck having a helical groove

adapted to receive said protuberances and permit said fitting to be screwed on said neck, a pawl carried by said fitting and adapted to engage one of said protuberances to prevent said fitting from being unscrewed from said neck, means on said neck to prevent access to said pawl, a frangible nonreplaceable diaphragm extending across an opening in said fitting to prevent passage of the contents of said container, and a removable closure adapted for leak-proof application to said fitting. 5

6. In a device of the class described, in combination, a container having a neck provided with a helical series of ratchet-like protuberances, a fitting for said neck having a helical groove 15 adapted to receive said protuberances and permit said fitting to be screwed on said neck, a pawl carried by said fitting and adapted to engage one of said protuberances to prevent said fitting from being unscrewed from said neck, a shoulder on 20 said neck to prevent access to said pawl, a frangible nonreplaceable diaphragm extending across an opening in said fitting to prevent passage of the contents of said container, and a removable closure adapted for leak-proof application 25 to said fitting.

7. In a device of the class described, in combination, a container element, a fitting element of molded plastic material, a helical series of ratchet-like protuberances on one of said elements, the other of said elements having a helical groove and a pawl, said pawl being adapted and arranged to override said protuberances when moved in one direction and to be stopped by one of said protuberances when moved in the other 30 direction, a frangible nonreplaceable diaphragm extending across an opening in said fitting element to prevent passage of the contents of said container element, the relative strengths of the fitting element and lock being such that force 35 applied to said lock through said fitting element will break said fitting element before effecting the release of said lock, and a removable and replaceable closure adapted for leak-proof application to said fitting. 40

8. In a device of the class described, in combination, a container having a neck provided with a helical series of ratchet-like protuberances, a fitting of molded plastic material for said neck having a helical groove adapted to receive said 50 protuberances and permit said fitting to be screwed on said neck, a pawl carried by said fitting and adapted to engage one of said protuberances to prevent said fitting from being unscrewed from said neck, means on said neck to prevent access to said pawl, a frangible nonreplaceable diaphragm extending across an opening in said fitting to prevent passage of the contents of said container, the relative strengths of 55 said fitting, said pawl and said protuberances being such that force applied to unscrew said fitting will break said fitting before effecting release of said pawl from one of said protuberances, and a removable and replaceable closure adapted 60 for leak-proof application to said fitting. 65

WILLIAM BAKER.
